UNITED STATES PATENT OFFICE.

ARTHUR H. GIBSON, OF EASTON, PENNSYLVANIA, ASSIGNOR TO THE INGERSOLL-SERGEANT DRILL COMPANY, OF NEW YORK, N. Y., A CORPORATION OF WEST VIRGINIA.

ROCK-DRILL.

No. 818,681.

Specification of Letters Patent.

Patented April 24, 1906.

Application filed August 26, 1905. Serial No. 275,851.

To all whom it may concern:

Be it known that I, ARTHUR H. GIBSON, a subject of the King of Great Britain and Ireland, and a resident of Easton, in the county 5 of Northampton and State of Pennsylvania, have invented a new and useful Improvement in Rock-Drills, of which the following is a specification.

My invention consists in certain improvements in that class of rock-drills in which the drills are operated by reciprocating columns of air.

The object of my invention is to provide manually-operated means for accurately adjusting the air-pressure in the tail-rod chamber of the drill, whereby the operation of the drill is facilitated.

In the accompanying drawings, Figure 1 represents my improved rock-drill in longitudinal central section with the drill-piston at a point intermediate the limits of its reciprocating movements. Fig. 2 is a detail longitudinal central section, on a greatly-enlarged scale, of the vent-screw; and Fig. 3 is a 25 top plan view of the vent-screw.

The shell of the drill is denoted by 1.

The cylinder is denoted by 2, its front head by 3, and its rear head extension by 4.

The piston-head of the drill is denoted by 5, its hollow tail-rod by 6, and its front rod by 7. This front rod extends through the front head 3 of the drill and is provided with the usual chuck 8 for the attachment of the drill-tool thereto.

35 The cylinder is adjusted along the shell 1 by the usual screw 9, mounted to rotate in a cross-bar 10 of the shell and turning in a traveling nut 11, carried by the drill-cylinder casing.

40 The rifle-bar is denoted by 12 and is mounted, as is usual, at the rear of the rear extension 4. The said bar extends forwardly into the interior of the hollow tail-rod 6 of the drill-piston and is there engaged by a nut 13, fixed to the tail-rod. This tail-rod is of substantially the same diameter as the front rod 7 and is fitted to slide in a sleeve 14, spaced from the inner walls of the rear extension 4, so as to form an annular space 15, which 45 space is connected with the space 16 back of the tail-rod through one or more holes 17 in the sleeve 14, the two spaces 15 and 16 thereby forming a tail-rod chamber.

A small vent opening or aperture lead-

from the tail-rod chamber to the external atmosphere as follows: A vent-screw 18 is screwed into the rear extension 4, which screw is provided with a tapered hole 19 therethrough. For the purpose of accurately adjusting the size of the vent opening or aperture from the tail-rod chamber to the external atmosphere, I provide a tapered plug or pin 20, having one side flattened, as shown at 21, which plug or pin is driven into the tapered bore 19 of the vent-screw. By 55 providing a number of these pins 20, each with a different amount of flattened surface, I am enabled to accurately adjust the size of this vent-opening to different presser-pres- 60 sures. It will be seen that when it is desired 70 to change the size of this vent-opening the screw 18 may be removed from the rear ex- 75 tension and the plug or pin 20 knocked out of the same and another plug with the required flattened surface driven in and the screw 80 again engaged with the rear extension. A washer 22 is located between the end of the sleeve 14 and the rotation device for the rifle- 85 bar for preventing the leakage of air there- 90 through. Another washer 23 surrounds the tail-rod 6 at the rear end of the piston-cham- 95 ber 24 at the front of the hollow sleeve 14 for preventing to as much a degree as possible the leakage of air from the piston-chamber 24 into the tail-rod chamber. Ports 25 26 100 open into the piston-chamber 24 at short distances from the ends of the chamber, the port 25 being connected to a fluid-pressure pipe 27 and the port 26 being connected to a fluid-pressure pipe 28, through which the 105 columns of air are reciprocated by the use of a presser, not shown herein.

I provide manually-operated means for accurately controlling the pressure of air in the tail-rod chamber as follows: A passage leads 110 from one of the fluid-pressure pipes 27 28, in the present instance the fluid-pressure pipe 28, to the annular space 15 of the tail-rod chamber, which passage in the present in- 115 stance is formed by means of a short pipe 100 connection 29, having one end opening into the pipe 28 and the other end into the said tail-rod chamber. In this pipe I provide a manually-operated valve 30, so that the amount of air which shall be permitted to es- 120 cape from the fluid-pressure pipe 28 to the in- 125 terior of the tail-rod chamber to raise the pressure in the tail-rod chamber to the de-

sired degree may be controlled to the most accurate degree.

In practice I find it desirable to give the tail-rod chamber a total capacity of about 5 twice that of the volume displaced by the tail-rod, so that when the tail-rod is moved into the chamber to the limit of its rearward movement there is still about half of the volume of the tail-rod chamber unoccupied. The mean 10 pressure of this tail-rod chamber above atmospheric pressure depends on the amount of air which is leaking past the washer 23 and the amount of air which is permitted to leak to the external atmosphere through the vent-opening hereinabove described. This pressure varies between zero and the mean fluctuating pressure in the pipe 28, depending entirely on the amount of leakage at the two points above referred to. By providing a 15 passage from the fluid-pressure pipe 28 to the tail-rod chamber and locating therein a manually-operated valve I am enabled to produce a device in which the amount of air-pressure in the tail-rod chamber may be accurately adjusted to the desired point to obtain 20 the best result in the operation of the drill-piston.

By the construction and arrangement of the parts as herein set forth I am enabled to 30 obtain a great percussive blow of the drill, for the reason that the compression of air in the tail-rod chamber during the rear stroke of the drill-piston will act as a strong elastic spring to force the tail-rod of the piston toward 35 the work. This force acts conjointly with the regular pressure on the back of the piston from the presser. Were it not for this pneumatic spring acting against the tail-rod the drill-piston would simply have a powerful 40 reciprocating action with comparatively poor percussive force.

It will be seen that by the use of the manually-operated valve in the passage leading from one of the fluid-pressure pipes to the 45 tail-rod chamber I am enabled to obtain to the greatest exactitude the amount of pressure in the tail-rod chamber which will produce the best result on the drill-piston tail-rod. It is to be understood that this manually-operated valve is only open to a very 50 small degree, and slight variations in its amount of opening materially affect the operation of the drill.

What I claim is—

55 1. A rock-drill piston having a tail-rod, a cylinder having a tail-rod chamber, and pipes for feeding the motive fluid to the opposite sides of the piston, said cylinder having a passage leading from one of the motive-fluid pipes to the tail-rod chamber.

60 2. A rock-drill piston having a tail-rod, a cylinder having a tail-rod chamber, pipes for feeding motive fluid to the opposite sides of the piston, said cylinder having a passage 65 leading from one of the motive-fluid pipes to

the tail-rod chamber and manually-controlled means for regulating the flow of air through said passage.

3. A rock-drill piston having a tail-rod, a cylinder having an extension provided with 70 a tail-rod chamber and having a vent-opening leading from said chamber to the external atmosphere, and motive-fluid-pressure pipes for the cylinder, said cylinder having a passage leading from one of said pipes to the 75 tail-rod chamber.

4. A rock-drill piston having a tail-rod, a cylinder having an extension provided with 80 a tail-rod chamber and having a vent-opening leading from said chamber to the external atmosphere, motive-fluid-pressure pipes for the cylinder, said cylinder having a passage leading from one of said pipes to the tail-rod chamber and a manually-operated valve 85 in said passage for controlling the flow of air from the pipe to the chamber.

5. A rock-drill piston having a tail-rod, a cylinder having an extension provided with 90 a tail-rod chamber and having a vent-opening leading from the chamber to the external atmosphere including a screw having a tapered bore and a pin removably engaged with the bore, said pin having a flattened side.

6. A tool-piston, having a front rod and a tail-rod, a cylinder having a tail-rod chamber, 95 pipes for feeding motive fluid alternately to the opposite sides of the piston and means for bringing the tail-rod chamber into open communication with one of the pipes.

7. A tool-piston having a front rod and a tail-rod, a cylinder having a tail-rod chamber, pipes for feeding motive fluid alternately to the opposite sides of the piston and means for bringing the tail-rod chamber into open 100 communication with the pipe which effects 105 the forward stroke of the tool.

8. A tool-piston having a front rod and a tail-rod, a cylinder having a tail-rod chamber, pipes for feeding motive fluid alternately to the opposite sides of the piston and a manually-operated valve for bringing the tail-rod chamber into and out of open communication 110 with one of said pipes.

9. A tool-piston having a front rod and a tail-rod, a cylinder having a tail-rod chamber, pipes for feeding motive fluid alternately to the opposite sides of the piston and a manually-operated valve for bringing the tail-rod chamber into and out of open communication 115 with the pipe which effects the forward stroke of the tool.

In testimony that I claim the foregoing as my invention I have signed my name, in presence of two witnesses, this 23d day of August, 1905.

ARTHUR H. GIBSON.

Witnesses:

FREDK. HAYNES,
HENRY THIEME.

It is hereby certified that in Letters Patent No. 818,681, granted April 24, 1906, upon the application of Arthur H. Gibson, of Easton, Pennsylvania, for an improvement in "Rock-Drills," errors appear requiring correction, as follows: In the specification and claims the word "presser" wherever it occurs should read *pressor* and the word "pressers" should read *pressors*; and that said Letters Patent should be read with these corrections therein that the same may conform to the record of the case in the Patent Office.

Signed and sealed this 15th day of May, A. D., 1906.

[SEAL.]

F. I. ALLEN,
Commissioner of Patents.
